UNITED STATES PATENT OFFICE.

WILLIAM TAYLOR, OF PEEKSKILL, NEW YORK, ASSIGNOR TO HIMSELF AND
GEORGE W. ROBERTSON, OF SAME PLACE.

MODE OF REPAIRING METALLIC PATTERNS.

SPECIFICATION forming part of Letters Patent No. 229,064, dated June 22, 1880.

Application filed May 10, 1880. (No model.)

To all whom it may concern:

Be it known that I, WILLIAM TAYLOR, of Peekskill, in the county of Westchester and State of New York, have invented a new and 5 useful Improvement in Modes of Repairing Metallic Patterns for Castings, of which the following is a specification.

Cast-iron patterns used in making castings, especially when thin or rendered delicate by 10 ornamentation, are liable to be broken by careless handling or in freeing them from the molding-sand by blows of the hammer or otherwise.

Heretofore the difficulty in mending these patterns when broken has been so great that it has been cheaper to replace them with new ones.

The present invention relates to a method or process by which metallic patterns, when broken, can be economically and practically 20 repaired; and it consists in forming a matrix in a mold from the pieces of the original pattern, removing the pieces from the mold, preparing them with holes and channels along the fractured edges, placing the prepared pieces 25 in the mold, and uniting them by running easily-fused metal into the holes and channels, substantially as hereinafter more fully set forth.

The invention is illustrated by the accompanying drawings, in which Figure 1 is a plan 30 view of a broken pattern. Fig. 2 is a plan view of the same after it has been repaired by this invention. Fig. 3 is a sectional view along the lines $x x$ and $x' x'$ of Fig. 2, showing the shape of the holes $b b$ and the channel $c c$; and Fig. 35 4 is a sectional view along the line $y y$ of Fig. 2, showing the shape of the main channel C.

In these drawings, A represents a pattern of cast-iron or other cast metal, broken into two pieces, a and a' , the line of fracture being 40 indicated by ff of Fig. 1.

The broken pattern is repaired in accordance with this invention by uniting the pieces a and a' in the following manner: A matrix is formed in the usual way in a mold by using the pieces 45 a and a' as patterns, their fractured edges being brought close together, as shown in Fig. 1, during the molding, so as to produce a matrix as near as practicable like one formed from the pattern A before it was broken. When 50 the pieces are taken from the mold any im-

perfections in the matrix caused by the sand entering the line of fracture or by the absence of small bits or pieces of the original pattern are to be removed by the molder in the usual way and with care, so as to make the matrix 55 as complete a copy of the original pattern as possible. The edges of the pieces a and a' are now cut away by grinding or filing, so that when they are replaced in the mold there will be a channel or opening between them for 60 the flow of the melted binding metal. This channel is designated in the drawings by C. Holes $b b$ are bored near the edge of each piece, and are connected with the edges by channels $c c$, formed by filing or grinding or cutting out 65 the metal with any suitable tool. These holes and channels should be of size and number to permit a sufficient quantity of the molten metal to unite with each of the pieces to firmly secure them together, and the holes are preferably to 70 be countersunk on both sides of the pieces, and the walls of the channels $c c$, as well as of the main channel C, are to be inclined or dovetailed, substantially as shown in Fig. 4 of the drawings, which construction will have the 75 effect to firmly lock the pieces together in all directions.

It may be observed that it will make no material difference to what extent the edges of the pieces bordering the line of fracture are 80 ground away, inasmuch as the configuration or ornamentation of the parts thus removed is already formed in the matrix and will be reproduced in the repaired pattern by the melted metal.

After the pieces have been prepared as above described they are replaced in the matrix of the mold, which they will fill, with the exception of the channel or space between the pieces and the small channels $c c$ and the holes $b b$, 90 all of which have been made since the matrix was formed by cutting away the metal of the pieces. The mold is then closed, and melted metal poured in at a gate arranged to connect with the space or channel between the pieces 95 a and a' , whereby this space, the channels $c c$, and the holes $b b$ are filled with the melted metal, which, upon cooling, firmly unites the different parts or pieces. Preferably an easily-fusible metal or alloy, which will contract 100

but slightly in cooling and is sufficiently soft to permit the surface of the pattern to be finished up or smoothed off, is used for the uniting metal.

- 5 Patterns broken into several pieces may be repaired in this manner, and whenever, as is frequently the case, some of the pieces are too small to be practically provided with holes and channels, and thereby united with the others, 10 such pieces, after being used to form the matrix, may be discarded and their places supplied with new metal in the operation of uniting the remaining pieces. This construction is illustrated in Fig. 5 of the drawings, in which the 15 small pieces *d d*, broken out of the central part of the pattern *D*, and the piece *e*, broken from its edge, after having been used in connection with the main part of the pattern to form the matrix, as above described, are discarded, and 20 only the fractured edges of the main or larger piece are prepared with channels and holes, as described. This main piece is then replaced in the matrix, and the places formerly occupied by the small discarded pieces are supplied

25 with the new metal, which is run into the mold through properly-located gates. In this case, as in that heretofore described, it will make no difference to what extent the fractured edges of the main piece are cut or ground away, as their impression has been transferred to the 30 matrix and will be reproduced in the part or parts formed by the running in of the new metal.

What is claimed as new is—

The hereinbefore-described mode of repairing metallic patterns, which consists in molding a matrix from the pieces of the original pattern, removing the pieces from the mold and preparing them with holes and channels 35 along their edges, replacing the prepared pieces 40 in the mold, and uniting them by running easily-fused metal between the pieces to fill the holes and channels, substantially as set forth.

WILLIAM TAYLOR.
